UNITED STATES PATENT OFFICE

WILLIAM LINDSAY, OF CHICAGO, ILLINOIS, ASSIGNOR TO ECONOMY FUSE AND MANUFACTURING COMPANY, OF CHICAGO, ILLINOIS, A CORPORATION OF NEW YORK

ELECTRIC SOCKET

Application filed February 25, 1928. Serial No. 256,850.

The present invention relates to improvements in electric sockets. Electric sockets as commonly used include an insulating member providing a supporting means for binding posts or the like for connection to the two wires of an electric circuit. Said insulating member also provides supporting means for a screw-threaded shell. Said supporting means is commonly housed 10 within a two-part casing. In many States of the United States the underwriters require that the casings of electric sockets be made of insulating material if said sockets are to be located in damp places. A problem is to 15 cure together the parts of such casings, inasmuch as no metal parts are ordinarily exposed exteriorly of the socket. The present invention constitutes an improvement over the structure disclosed in an application filed 20 by David D. Gordon on March 23, 1927, Serial No. 177,480.

An object of the present invention is to provide a construction in which the spring members utilized in said Gordon application are 25 positively actuated by the skirt portion of the socket to actuate the free ends of said spring members to insure a positive locking action.

A further object of the present invention is to provide an electric socket mechanism 30 which may be readily assembled and which securely holds the parts in assembled relationship.

A further object is to provide an electric socket assembly which is cheap to manufacture, which may be assembled on a quantity basis at a relatively low cost, which is sturdy, and which provides a positive locking action of improved design to hold the parts in assembled relationship.

40 Further objects will appear as the description proceeds.

Referring to the drawings—

Figure 1 is a view in side elevation of an electric socket embodying the principles of 45 the present invention;

Figure 2 is a longitudinal sectional view of the structure shown in Figure 1;

Figure 3 is a view similar to Figure 1 but showing the skirt portion removed;

50 Figure 4 is a sectional view illustrating the

skirt for cooperation with the parts shown in Figure 3;

Figure 5 is a perspective view of a holding member used in the practice of the present invention, and

55 Figure 6 shows a detail of a latch forming part of the present invention, an extremity thereof being shown in its bent position, somewhat exaggerated.

The particular socket assembly chosen for 60 illustration embodies switching means, the switching means illustrated being of the pull chain variety. The present invention is not limited to socket mechanisms embodying switching means, and for this reason the 65 switching mechanism need not be described in detail.

The numeral 1 indicates a supporting member 70 which will preferably be composed of insulating material. Said supporting member provides a base for certain switching mechanism, indicated as a whole by the numeral 2, which switching mechanism includes a bell mouth 3 forming a chain guide for the pull chain 4. The supporting member 1 also 75 provides a support for the shell 5, which according to ordinary practice may be formed of sheet metal. Said shell 5 is screw-threaded both externally and internally, the thin sheet metal providing said internal and external screw-threads. The supporting member 1 and the parts supported thereby may 80 take the form usual in present practice, but should be provided with a shoulder 6, for a purpose which will appear hereinafter.

85 The insulating member 1, the shell 5 and the parts connected thereto are mounted within a housing or casing comprising the cap 7 and the skirt 8, which in a preferred embodiment of the present invention are both made of insulating material. If made of other than insulating material, it will be understood, of course, that the electrical conducting parts of the socket will be properly insulated from said housing or casing comprising the cap 7 and the skirt 8. The inner wall 8^a of the skirt 8 is 90 frusto-conical in contour in that portion thereof which is adjacent to the cap 7.

95 The cap 7 provides the aperture 9 for the admission of the two wires of an electric cir-

55

cuit. Said two wires will be connected to the two binding posts (not shown) which are commonly provided within an electric socket. Said cap 7 is slotted at its edge portion, as indicated by the numeral 10, for the reception 5 of the chain guide 3. The supporting member 1 fits within a shouldered portion 11 on the interior of the cap 11 close to the upper extremity thereof. Secured to the cap 11 are 10 a plurality of resilient holding members or latches 12-12 having bent over portions adapted to be secured to the cap 7 by means of screws 13 or other preferred holding means. Each of the resilient holding members 12 is 15 provided with the shoulder 14 disposed adjacent to the lower extremity of the corresponding holding member 12. Said shoulders 14 are adapted to snap over the annular shoulder 6 which is rigid with the insulating member 1, 20 whereby to hold the insulating member 1 and its associated parts releasably within the cap 7. The free end of each of the holding members 12 is provided with the piloting portion 15 at its extremity, whereby the annular shoulder 6 may be readily snapped into cooperating relationship with the shoulders 14-14 of the holding members 12. Said shoulders 14-14 are preferably rounded, whereby to simplify the matter of snapping 25 the annular shoulder 6 past said shoulders. 30

The lower extremity of the cap 7 is provided with the shouldered portion 16 and adapted to receive a corresponding shouldered portion 17 on the upper side of the 35 skirt 8. The interior of the skirt 8 is screw-threaded, as indicated by the numeral 18, which screw-threaded portion is adapted to mesh with the external screw-threads of the shell 5. If preferred, a metal lining 19 may 40 be provided within the screw-threaded portion of the skirt 8 for engagement with the shell 5. The inner wall 8^a of the skirt 8 is so designed relative to the free extremities 15 of the latches 12-12 that as the skirt 8 is 45 turned up upon the screw-threaded shell 5, said wall 8^a will positively actuate said extremities 15-15 inwardly, whereby a positive locking action is had between the shoulders 14-14 of said latches 12-12 and the shoulder 6 of the supporting member 1. 50 The taper of the wall 8^a is so chosen that said extremities 15-15 of the latches 12-12 are placed under spring tension, being positively moved inwardly about the shoulder 6 as a 55 fulcrum.

It will be clear without detailed explanation that the parts may be readily disassembled by unscrewing the skirt 8 from the shell 5, after which the insulating member 1 may 60 be snapped past the shoulders 14 of the holding members 12 and whereby the extremities of the two wires of an electric circuit may be conveniently secured to the binding posts (not shown) on said insulating member 1. 65 After the electric circuit wires have been se-

cured in place, the insulating member 1 and its attached parts may be snapped into position with the shoulders 14 of the holding members 12 in holding relationship with the annular shoulder 6. The skirt 8 may then be placed in position upon the shell 5 and screwed home. As noted above, the screwing home of the skirt 8 will actuate the extremities 15-15 toward the axis of the socket, tending to swing said extremities about the shoulder 6 as a fulcrum, the result being that a positive locking action is had, said action being the more positive the further up the skirt 8 is screwed. 70 75

By reason of the fact that the shell is a complete cylinder, the skirt 8 may be screwed home without danger of stripping the threads upon said shell member. A tight wedging action is therefore had between the screw-threads of the shell 5 and the skirt 8, whereby said skirt 8 is held securely in position. 80 85

The present invention presents the advantages not only that the cost of assembly at the factory is greatly reduced, but the task of the person installing the socket is very 90 greatly simplified.

Though a preferred embodiment of the present invention has been described in detail, many modifications will occur to those skilled in the art. It is intended to cover all such modifications that fall within the scope 95 of the appended claims.

What is claimed is—

1. In an electric socket, in combination, a two-part housing comprising a cap and a skirt, means within said housing for supporting circuit connector means, and resilient latch members secured to said cap and having latching engagement with said supporting means, said supporting means having shoulder means, said latch members having movable extremities, said skirt having a portion adapted to exert a force upon said extremities to bend same about said shoulder means. 100 105 110

2. In an electric socket, in combination, a cap, a skirt, means within said cap and skirt including a screw-threaded cylindrical shell adapted to receive an electric plug, said means including a shoulder, and a latch within said cap adapted to engage said shoulder to retain said means within said cap, said skirt having a screw-threaded portion engaging the screw-threads of said shell, said latch having a bendable extremity, said skirt having a portion adapted to exert force upon said extremity to bend same about said shoulder. 115 120

3. In an electric socket, in combination, a two-part housing comprising a cap and a skirt, means within said housing for supporting circuit connector means, and a resilient latch member secured to said cap and having latching engagement with said supporting means, said latch member having a 125 130

bendable extremity, said skirt having a portion adapted to exert force upon said extremity to bend same about said supporting means as a fulcrum.

- 5 4. In an electric socket, in combination, a cap, a skirt, means housed within said cap and skirt, said means including a shouldered portion, and a resilient latch for releasably holding said means within said cap, said means 10 and said skirt having cooperating screw-threads, said skirt and said cap having portions abutting one another when said skirt is screwed home upon the screw-threads of said means, said latch having a bendable extremity, said skirt having a portion for positively moving said extremity about said shouldered portion as a fulcrum into latching engagement with said shouldered portion, whereby when said skirt is screwed home 15 upon said screw-threads of said means, said shouldered portion will be securely latched and the threads upon said means and said skirt will be brought into jamming relationship with one another.
- 20 5. In an electric socket, in combination, a cap, a skirt, means housed within said cap and skirt, said means including an externally screw-threaded cylindrical socket member, said skirt having screw-threads cooperating with said externally threaded socket member, said cap and skirt having portions positioned to abut when said skirt is screwed home upon said socket member, and a latch secured to said cap and having latching relationship with said means, said latch having 25 a bendable extremity, said skirt having a portion adapted to positively move said extremity about said shouldered portion as a fulcrum when said skirt is screwed home upon 30 said socket member, whereby when said skirt is screwed home as aforesaid the screw-threads on said skirt and upon said socket member will be brought into jamming relationship with one another and said latch will 35 be brought into positive latching engagement with said means.
- 40 6. In an electric socket, in combination, a cap, a skirt, means housed within said cap and skirt, said means including a shouldered portion, and a latch for releasably holding said means within said cap, said means and said skirt having cooperating screw-threads, and said skirt and said cap having portions adapted to abut when said skirt is screwed 45 home upon said means, said latch having a bendable extremity, said skirt having a portion for positively moving said extremity about said shouldered portion as a fulcrum into latching engagement with said means.
- 50 7. In an electric socket, in combination, a cap, a skirt, means housed within said cap and skirt including a screw-threaded shell adapted to receive an electric plug, said means including a shoulder, and a latch within said 55 cap adapted to engage said shoulder to retain 60

said means within said cap, said latch having a bendable extremity, said skirt having a screw-threaded portion engaging the screw-threads of said shell, said skirt having a portion for positively moving said extremity about said shoulder to insure the latching functions of said latch.

Signed at Chicago, Illinois, this 23rd day of February, 1928.

WILLIAM LINDSAY.
